[57] **CLAIM**

The ornamental design for a amplifier for automobile, substantially as shown.

DESCRIPTION

FIG. 1 is a front elevational view of an amplifier for automobile embodying my design;

FIG. 2 is a rear elevational view thereof;

FIG. 3 is a side (the other side is a mirror image of this side view)

FIG. 4 is a top plan view thereof;

FIG. 5 is a bottom plan view thereof; and

FIG. 6 is a perspective view of the amplifier.
